UNITED STATES PATENT OFFICE.

EMILE POUYAT, OF LIMOGES, FRANCE, ASSIGNOR TO THE SOCIÉTÉ LA CÉRAMIQUE, J. POUYAT, OF SAME PLACE.

DESIGN FOR A DISH.

SPECIFICATION forming part of Design No. 21,406, dated March 15, 1892.

Application filed January 28, 1892. Serial No. 419,618. Term of patent 3½ years.

To all whom it may concern:

Be it known that I, EMILE POUYAT, of Limoges, France, a citizen of France, have invented a certain new Design for Table-Ware, 5 of which the following is a specification.

In the accompanying drawings, Figure 1 is a perspective view of a soup-tureen and its cover embodying my design for dishes. Fig. 2 is a top view of the cover.

- 10 The leading features of my design consist of the shape of the dishes and covers and of a flat relief scalloped leaf ornament, arabesque angle ornaments at the ends of said scalloped leaf ornaments, flat relief subdividing-lines
- 15 between the ends of the leaf ornament, outwardly and upwardly extending U-shaped dish-handles terminating in flower ornaments and having the top cross-piece scalloped, and a twisted central cover-handle provided with
- 20 leaf ornaments, and a base having notches and leaf ornaments on the edges of said notches. The articles of dishes have an approximately oval shape in plan view divided into four curved sections with slight curved projections
- 25 at the meeting ends. The sides of the dishes are curved downward and have the offsets *n* near the base.

A represents a tureen. B represents the cover of the same.

a is a flat relief scalloped leaf ornament. 30

b are flat relief arabesque angle ornaments at the ends of the leaf ornament *a*.

d are flat relief division ornamental lines between the ends of the ornaments *a*.

D are the outwardly and upwardly extending bracket-handles. *f* are leaf ornaments at the ends of the same. 35

g is the scalloped cross-piece of the handle.

E is the twisted cover-handle; *h*, the ornaments of the same; *k*, the leaf ornaments on 40 the ends of the same.

l are notches in the base, and *m* leaf ornaments on the edges of said base.

What I claim is—

The design for dishes, substantially as herein shown and described. 45

In testimony that I claim the foregoing as my invention I have signed my name in presence of two subscribing witnesses.

EMILE POUYAT.
